(57) **CLAIM**

The ornamental design for an accent light, as shown and described.

DESCRIPTION

FIG. 1 is a front elevational view of the accent light according to our new design;

FIG. 2 is a left side elevational view, the right side view being a mirror image;

FIG. 3 is a top plan view thereof;

FIG. 4 is a bottom plan view thereof; and,

FIG. 5 is a perspective view thereof, looking toward the lower left front side.

The rear of the fixture is plain and non-ornamental.
